UNITED STATES PATENT OFFICE

ANDRÉ GARBARINI, OF COURBEVOIE, FRANCE, ASSIGNOR, BY MESNE ASSIGNMENTS, TO LIBBEY CATAPHOTE CORPORATION, OF TOLEDO, OHIO, A CORPORATION OF OHIO

HOLDER FOR AUTOCOLLIMATORS

Application filed August 25, 1930. Serial No. 477,669.

The present invention relates to a holder for autocollimating devices and in particular for such autocollimators as comprise an objective lens, preferably hemispherical, and 5 a reflector formed integral therewith or joined thereto by means of an appropriate cementing or binding agent.

One object of the present invention is to provide a holder that can be easily assembled and which has a low manufacturing cost.

Another object of the present invention is to provide a holder that can be easily secured to a wood or metal panel and which 15 cannot be removed by an unauthorized person.

A further object of the invention is to provide a form of holder which will keep out the dust and prevent the humidity from 20 penetrating to the metal-coated backing surface of the reflector of the autocollimator.

Yet a further object of the invention is to provide a holder which when fixed on painted characters will give an impression of 25 relief without affecting the visibility. To these and other ends, the invention consists in certain improvements, combinations and arrangements of parts, all as will be herein-after more fully described, the features of 30 novelty being pointed out particularly in the claims at the end of the specification.

In the accompanying drawing:

Fig. 1 represents a central vertical section of the assembled holder mounted on a 35 metal panel,

Fig. 2 illustrated a detail of a nut device soldered to the metal panel to take the holder and

Fig. 3 is a plan view of the holder.

40 The holder comprises an outer shell 1 stamped to form a portion of a sphere within which is housed the reflector 2 of an autocollimating lens joined to or integral with a hemispherical object lens 3 projecting from 45 the apertured end of the holder which makes a snug fit with the autocollimator at the joining surface 3^a of the reflector 2 and object lens 3 so as to keep out the dust and prevent the humidity from making its way to 50 the metal-coated reflecting surface 4 of the

reflector. Within the opposite open end of the shell 1 is mounted a member 5 stamped out to form a cup which is secured to the shell 1 in any suitable manner. Between the flat bottom 6 of the cup 5 and the reflector 2 is inserted a filling member such as a felt 7. The bottom 6 of the cup 5 has a central opening which may be apertured or tapped to take a screw 7^a adapted to be screwed into the wood or metal panel on which it is desired to mount the holder. In order to prevent unauthorized removal of the holder once it has been mounted on the panel, the cup member 5 has tabs 8 struck up from the bottom 6 as shown in Figs. 1 and 3. 55 When the holder is mounted on a wooden panel, the tabs 8 only allow rotation of the holder in one direction, namely that in which the screw 7^a makes its way into the wood, but prevents rotation of the screw in the opposite direction to withdraw the holder by biting into the wood panel. These tabs can 60 however be dispensed with when it is not desired to prevent removal of the holder. 65

Fig. 1 illustrates an arrangement for 70 mounting the holder on a metal panel 9. On the face of the panel 9 is soldered or otherwise secured a plate 10 having a raised portion 11 stamped out in the form of a square or hexagonal nut, a similar square or hexagonal nut 12 being lodged in the gap between the panel 9 and the stamped raised portion 11 of the plate 10. An opening is formed in the stamped portion 11 through which passes the screw 7^a of the holder 75 which screws into the nut 12. As the holder is screwed home, the tabs 8, owing to their shape, easily pass over the wings of the plate 11, but when an attempt is made to rotate the holder in the opposite direction, the tabs 8 abut against the plate 11 and prevent rotation. 80

Naturally, when the holder is mounted on a wooden panel, the stamped plate 10 may be dispensed with, the tabs 8 biting directly into the wood. 90

I claim:

1. A holder for autocollimating devices including a reflector and an objective lens joined thereto, said holder comprising a 100

stamped shell housing said reflector and shaped to fit snugly about the joining surface of said reflector and objective, a stamped cup member engaged within the 5 outer end of said shell with its bottom turned inwards, a filling member inserted between the bottom of said cup member and said reflector, a screw mounted in said cup member, and a panel member having a portion 10 in which said screw is screwed to mount said holder on said panel.

2. A holder for autocollimating devices including a reflector and an objective lens joined thereto, said holder comprising a 15 stamped shell housing said reflector and shaped to fit snugly about the joining surface of said reflector and objective, a stamped cup member engaged within the outer end of said shell with its bottom 20 turned inwards, a filling member inserted between the bottom of said cup member and said reflector, a screw mounted on said cup member, a panel member having a portion in which said screw is screwed to mount said 25 holder on said panel, and tab portions struck up from the bottom of said cup member and adapted to engage with said panel to prevent unauthorized removal of said holder.

3. A holder for autocollimating devices 30 including a reflector and an objective lens joined thereto, said holder comprising a stamped shell housing said reflector and shaped to fit snugly about the joining surface of said reflector and objective, a 35 stamped cup member engaged within the outer end of said shell with its bottom turned inwards, a filling member inserted between the bottom of said cup member and said reflector, a screw mounted on said cup 40 member, a panel member, a plate secured to said panel and including a stamped central portion spaced from said panel, a nut lodged in the gap between said stamped plate portion and said panel and in which said screw 45 is adapted to engage, and tab portions struck up from the bottom of said cup member and adapted to engage with the nonstamped ends of said plate to prevent removal of said holder.
